US00D993953S

(12) **United States Design Patent** (10) **Patent No.:** **US D993,953 S**
(45) **Date of Patent:** **** Aug. 1, 2023**

(54) **SET OF WIRELESS HDMI TRANSMITTER AND RECEIVER**

(71) Applicant: **Wenqi Song**, Shenzhen (CN)

(72) Inventor: **Wenqi Song**, Shenzhen (CN)

(**) Term: **15 Years**

(21) Appl. No.: **29/814,308**

(22) Filed: **Nov. 4, 2021**

(30) **Foreign Application Priority Data**

Oct. 25, 2021 (EM) 008734198-0001

(51) **LOC (14) Cl.** **14-02**

(52) **U.S. Cl.**

USPC **D14/358; D14/230**

(58) **Field of Classification Search**

(57) **CLAIM**

The ornamental design for a set of wireless HDMI transmitter and receiver, as shown and described.

DESCRIPTION

FIG. 1 is a perspective view of a receiver of a set of wireless HDMI transmitter and receiver, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a transmitter of the set of wireless HDMI transmitter and receiver, shown separately for ease of illustration;

FIG. 10 is another perspective view thereof;

FIG. 11 is a top plan view thereof;

FIG. 12 is a bottom plan view thereof;

FIG. 13 is a left side elevational view thereof;

FIG. 14 is a right side elevational view thereof;

FIG. 15 is a front elevational view thereof;

FIG. 16 is a rear elevational view thereof; and,

FIG. 17 is a perspective view of the set of wireless HDMI transmitter and receiver.

The broken lines in the drawings depict portions of the set of wireless HDMI transmitter and receiver that form no part of the claimed design.

1 Claim, 17 Drawing Sheets
